UNITED STATES PATENT OFFICE.

FRANCIS J. COLE, OF NEW YORK, N. Y., ASSIGNOR TO AMERICAN LOCOMOTIVE COMPANY, OF NEW YORK, N. Y., A CORPORATION OF NEW YORK.

SUPERHEATER.

No. 849,052.

Specification of Letters Patent.

Patented April 2, 1907.

Application filed September 14, 1906. Serial No. 334,663.

To all whom it may concern:

Be it known that I, FRANCIS J. COLE, of the borough of Manhattan, in the city and State of New York, have invented a certain new and useful Improvement in Steam-Boiler Superheaters, of which improvement the following is a specification.

My present invention relates to superheaters of the general class or type in which the superheater-pipes are located in fire-tubes of a steam-boiler, an instance of which is exemplified in Letters Patent of the United States No. 765,307, granted and issued to the American Locomotive Company, as my assignee, under date of July 19, 1904.

The object of my invention is to provide a superheater of such general type which shall embody as characteristic features of improvement a substantial reduction in the number of joints required to be made and maintained steam-tight; capability of ready removal and replacement of one or more pairs of superheater-pipes without interference with the remainder of the appliance; capability of removal and replacement of any one or more of a set of vertical headers for renewal or repairs of the boiler-tubes in front of which they are located without disturbing other parts; tight and secure connections between the superheater-pipes and headers, and exemption from any perceptible degree of cooling of the superheated steam by the action thereon of saturated steam during the passage of the latter from the boiler to and through the superheating appliances.

The improvement claimed is hereinafter fully set forth.

In the accompanying drawings, Figure 1 is a vertical longitudinal section through the forward portion of a locomotive-boiler, illustrating an application of my invention; Fig. 2, a vertical transverse section through the smoke-box, showing the headers at the right side of the figure in elevation, two of those toward the left portion partly in section and one header at the left side removed and the adjoining header broken away, disclosing the front ends of the superheating-tubes; Fig. 3, a view in vertical transverse section, on an enlarged scale, of the lower portions of two adjoining headers; Fig. 4, a front view, partly in elevation and partly in section and on an enlarged scale, of the T-head; Fig. 5, a horizontal section through two adjoining headers

and through portions of two superheating fire-tubes and superheater-pipes located therein and connected at their front ends to the headers; Fig. 6, a front view, on an enlarged scale, of portions of three adjoining headers, showing, partly in section, the superheater-pipes connected thereto; and Fig. 7, a side view, on the same scale, of a portion of a header, showing a lateral ear or connection-chamber thereof and its connections in section.

My invention is herein, as in Letters Patent No. 765,307 aforesaid, set forth as applied in connection with a locomotive-boiler 4, which is of the ordinary construction, and is provided at its forward end with a smoke-box 4^a. A plurality of fire-tubes 4^b, ordinarily of comparatively small diameter, extend from the fire-box at the rear end of the boiler, which is not shown, to the front flue-sheet 4^c, and the products of combustion pass through said tubes and through a number of tubes 67, of larger diameter, which are located in the upper and middle portion of the space within the boiler and which will be herein descriptively termed "superheating-tubes" to the smoke-box 4^a, from which they are discharged into the atmosphere through a stack in the ordinary manner. Steam is supplied from the boiler to the cylinders through a main steam-pipe or dry pipe 61, passing through the front flue-sheet 4^c and connected in front thereof to a transverse T-head 62 62^b, from which it is conducted through superheater-pipes 69, which with their connections will be presently described, and after being superheated in said pipes passes to the cylinders through branch steam-pipes 63, located on opposite sides of the smoke-box.

In the practice of my invention I locate in each of the superheating-tubes 67 one or more pairs (preferably, as shown, an upper 95 and a lower pair) of superheater-pipes 69, said pipes extending longitudinally in the superheating-tubes from a vertical plane a short distance—say thirty inches or thereabout—forward of the fire-box flue-sheet 100 to vertical planes in the smoke-box forward of the front flue-sheet. The superheater-pipes of each pair are connected in U form at their rear ends, as by a return-bend 69^d, and are held up in normal position in the superheating-tubes by any suitable and preferred supports—as, for example, those set forth in Letters Patent of the United States,

No. 782,489, granted to American Locomotive Company, as my assignee, February 14, 1905. The superheater-pipes 69 are open at their forward ends, at which they communicate, through connections hereinafter described, with the main steam-supply pipe 61 and the branch or delivery steam-pipes 63, respectively, so as to constitute continuous avenues or channels throughout the length of which the steam which is to be superheated traverses from the supply steam-pipe to the branch or delivery steam-pipes.

The T-head is, as heretofore, located in front of the upper portion of the front of the sheet 4^d and comprises a supply-compartment 62, to the middle of which the main supply steam-pipe or dry pipe 61 is connected in the usual manner, and a delivery-compartment 62^c, which in this instance is located below the front portion of the supply-compartment and is separated therefrom by a partition-wall, which may, if preferred, be made double, so as to provide an intervening space for preventing transfer of heat from one compartment to the other. The branch or delivery steam-pipes 63 are connected to the ends of the delivery-compartment 62^c.

A plurality of vertical saturated steam-headers 70 extend downwardly from the front portion of the supply-compartment 62 of the T-head and a plurality of vertical superheated-steam headers 70^c, substantially similar in form, but of different length, extend downwardly from the front portion of the delivery-compartment 62^c of the T-head. The saturated and superheated steam headers are respectively alternated in position across the front of the T-head, and the central planes of the headers are located on opposite sides of the central planes of the vertical rows of superheating-tubes 67. The headers 70 70^c are each independently insertible on and removable from the T-head and are detachably secured thereto by bolts 71. Ports 62^b in the front wall of the supply-compartment 62 of the T-head register with corresponding ports in the rear walls of the saturated-steam headers 70 at the tops thereof, and ports 62^c in the front wall of the delivery-compartment 62^c of the T-head register with corresponding ports in the rear walls of the superheated-steam headers 70^c at the tops thereof.

The connection of the ends of the steam-superheating channels formed by the superheater-pipes 69 to the saturated and the superheated steam headers, respectively, in such manner as to effect a reduction in the number of steam-tight joints, insure tight joints, and admit of the ready and convenient attachment and detachment of any one or more pairs of superheater-pipes to and from the headers, is a leading and character-

istic feature of my invention. The construction herein exemplified as desirably adapted for the attainment in practical and regular service of the results above stated is as follows.

Lateral tubular ears or connection-chambers 70^k are formed integral with the body of each of the saturated and superheated steam headers 70 70^c, said ears being so disposed in number and location on the several headers that there shall be an ear on each header in advance of each of the several superheating-tubes 67, which adjoin said header. Thus, as will be seen from Fig. 2, the two outer superheated-steam headers 70^c are provided with two ears on their inner sides in advance of the two adjoining superheating-tubes and have no ears on their outer sides, there being no superheating-tubes adjoining them on those sides. All of the intermediate headers, each of them being located between two vertical rows of superheating-tubes, are provided with ears on both sides, the ears corresponding in number and location on the headers with the adjoining superheating-tubes.

The ears 70^k are open at their front and rear ends, at which they are recessed, to receive a suitable packing, (which in this instance is shown as a copper ring 70^m), against which packings collars 69ⁿ on the front ends of the pairs of superheater-pipes 69 abut, and the pipe-collars are adjusted and held to a tight bearing on the packings by rocking or curved-faced glands or followers 70ⁿ, fitting against the pipe-collars and connected by bolts 70°, extending above and below the ears and provided with nuts 70^p on their ends. The forward end of one of the pipes of each pair of superheater-pipes is connected in the manner above described to an ear 70^k on one of the saturated-steam headers 70, and the forward end of the other pipe of the pair is similarly connected to an adjacent ear on one of the superheated-steam headers 70^c. The provision for the traverse of steam through the superheater-pipes from the saturated to the superheated-steam headers will more clearly appear by reference to the horizontal section, Fig. 5, from which it will also be seen that the superheater-pipes of the lower pair in each superheating-tube are connected to the rear ends of the ears of a saturated and a superheated steam header, respectively, while the pipes of the upper pair in the same tube are connected to the front ends of the same ears. The pipes of the upper pairs are bent downwardly and rearwardly in front of the ears in order to bring their ends into line axially with the ears and are also bent outwardly or away from the central planes of the vertical rows of superheating-tubes, so as to leave clear spaces around the nuts 70^p of the connecting-bolts 70° for the application of a

wrench in screwing them to the required bearing on the adjacent glands 70^a. The plugs shown in the lower ends of the headers are provided merely for closing the openings left therein in coring them and are not intended to be removed in the use of the appliance. The connection of the superheater-pipes to the headers in the manner above described has the further advantage of enabling the front openings in the headers and their removable closing-plugs, which have been used in several prior constructions of the general type to which my invention relates, to be entirely dispensed with.

In operation saturated steam from the boiler passes through the dry pipe 61 into the supply-compartment 62 of the T-head and thence into the set of communicating saturated-steam headers 70, from which it passes, first rearwardly and then forwardly, through the pairs of connected superheater-pipes 69 and thence into and through the communicating superheated-steam headers 70^f, being in its traverse through the headers 70 and superheater-pipes thoroughly superheated by the hot products of combustion which pass through the superheating-tubes inclosing the superheater-pipes and through the smoke-box. The superheated steam passes from the superheated-steam headers 70^f into the communicating delivery-compartment 62^f of the T-head and thence through the branch steam-pipes 63 to the engine-cylinders for utilization therein.

It will be obvious to those familiar with locomotive-boiler construction and operation that the assembling and taking down of the entire superheating appliance and the removal and insertion of any desired part or parts thereof as may from time to time become necessary or desirable are greatly facilitated by the provision of the independently attachable and detachable vertical headers and the connection of the superheater-pipes to lateral tubular ears on the saturated and superheated steam-headers alternately in the manner herein set forth. Any of the headers and its connected pipes may be readily taken down and replaced without disturbing the remainder of the apparatus in case renewal or repair of a boiler tube or tubes behind such header should be required, and by merely removing four bolts any pair of superheater-pipes can be withdrawn without interference with any part of the appliance exterior to the superheating-tube on which said pair of pipes is located. The number of joints is substantially reduced as compared with prior constructions, and the improved manner of connecting the superheater-pipes to the headers enables tight joints at these connections to be effectually made and maintained. It will further be seen that as the saturated and superheated steam headers are completely sepa-

rated and as no opportunity for transfer of heat from the superheated to the saturated steam is afforded except throughout the limited area of the partition-wall which separates the two compartments of the T-head (which wall may, as before stated, be made double, if desired, with an intervening air-space) no perceptible or substantial loss of heat from such transfer will be found in practice. The form and location of the headers 75 are also such as to expose a large area of effective heating-surface to the action of the hot products of combustion passing through the smoke-box.

I claim as my invention and desire to secure by Letters Patent—

1. The combination, with a tubular steam-boiler, of a T-head divided into supply and delivery compartments, a vertical saturated-steam header and a vertical superheated-steam header communicating, respectively, with the supply and the delivery compartments, and a pair of superheater-pipes communicating at their forward ends with the saturated and the superheated steam headers, respectively, and connected laterally to said headers.

2. The combination, with a tubular steam-boiler, of a T-head divided into supply and delivery compartments, a vertical saturated-steam header and a vertical superheated-steam header, each extending downwardly from the T-head, and communicating, respectively, with the supply and the delivery compartments thereof, and a pair of superheater-pipes communicating at their forward ends with the saturated and the superheated steam headers, respectively.

3. The combination, with a tubular steam-boiler, of a T-head divided into supply and delivery compartments, a vertical saturated-steam header and a vertical superheated-steam header independently and detachably connected to said T-head and communicating, respectively, with the supply and the delivery compartments thereof, and a pair of superheater-pipes communicating at their forward ends with the saturated and the superheated steam-headers, respectively.

4. The combination, with a tubular steam-boiler, of a T-head divided into supply and delivery compartments, a vertical saturated-steam header and a vertical superheated-steam header communicating with the supply and the delivery compartments, respectively, a superheating-tube located below the T-head, and a pair of superheater-pipes extending in the superheating-tube, and communicating, through lateral connections, with the saturated-steam header and the superheated-steam header, respectively.

5. The combination, with a tubular steam-boiler, of a T-head divided into supply and delivery compartments, a vertical saturated-steam header and a vertical superheated-

- steam header communicating with the supply and the delivery compartments respectively, superheating-tubes located below the T-head, pairs of superheater-pipes extending in the superheating-tubes, and lateral connections through which one pipe of each pair communicates with the saturated-steam header and the other pipe of said pair communicates with the superheated-steam header.
10. The combination, with a tubular steam-boiler, of a T-head divided into supply and delivery compartments, superheating-tubes, vertical saturated-steam headers communicating with the supply-compartment and having lateral tubular ears, vertical superheated-steam headers communicating with the delivery-compartment and having lateral tubular ears, and pairs of superheater-pipes located in the superheating-tubes and connected at their front ends to ears on a saturated and a superheated-steam header, respectively.
11. The combination, with a tubular steam-boiler, of a T-head divided into supply and delivery compartments, superheating-tubes, vertical saturated-steam headers communicating with and connected detachably to the supply-compartment and having lateral tubular ears, vertical superheated-steam headers communicating with and connected detachably to the delivery compartment having lateral tubular ears, and pairs of superheater-pipes located in the superheating-tubes and connected at their front ends to ears on a saturated and a superheated steam header, respectively.
12. The combination, with a tubular steam-boiler, of a T-head divided into supply and delivery compartments, a vertical saturated-steam header and a vertical superheated-steam header communicating, respectively, with the supply and the delivery compartments, a pair of superheater-pipes communicating at their forward ends with the saturated and the superheated steam headers, respectively, and connected to the rear ends of lateral tubular ears on said headers, and a pair of superheater-pipes communicating at their forward ends with the saturated and the superheated steam headers, respectively, and being bent downwardly and rearwardly and connected to the front ends of lateral tubular ears on said headers.
13. The combination, with a tubular steam-boiler, of vertical rows of superheating-tubes, pairs of superheater-pipes extending longitudinally therein, fittings connecting the ends of the pipes of each pair nearer the firebox, a main steam-supply pipe, a steam-delivery pipe, a plurality of vertical saturated-steam headers and vertical superheated-steam headers, disposed, in alternated position, in advance of the superheating-tubes, and communicating with the steam-supply pipe and with the steam-delivery pipe, respectively, and connections coupling the forward ends of each pair of superheater-pipes to a saturated-steam header and to a superheated-steam header, respectively, upon the sides of said headers.
14. The combination, with a tubular steam-boiler, of a plurality of saturated-steam headers, each communicating with a steam-supply pipe, a plurality of alternately-disposed superheated-steam headers, each communicating with a steam-delivery pipe, all of said headers being formed with lateral tubular ears or connection-chambers, a plurality of pairs of superheater-pipes, and connections coupling the forward ends of each pair of superheater-pipes to ears on a saturated-steam header and a superheated-steam header, respectively.
15. The combination, with a tubular steam-boiler, of a plurality of saturated-steam headers, each communicating with a steam-supply pipe, a plurality of alternately-disposed superheated-steam headers, each communicating with a steam-delivery pipe, all of said headers being formed with open-ended lateral tubular ears or connection-chambers, a plurality of pairs of superheater-pipes having their forward ends coupled to the rear ends of ears on a saturated and a superheated steam header, respectively, and a plurality of pairs of superheater-pipes having their forward ends coupled to the forward ends of ears on a saturated and a superheated steam header, respectively.
16. In a steam-boiler superheater, the combination of a vertical casing or header having an upper port or opening for communication with a T-head compartment and lateral tubular ears or connection-chambers, and superheater-pipes connected to said lateral connection-chambers.
17. In a steam-boiler superheater, the combination of a vertical casing or header having an upper port or opening for communication with a T-head compartment and lateral open-ended tubular ears or connection-chambers, superheater-pipes having straight ends connected to the rear ends of said lateral connection-chambers, and superheater-pipes having downwardly and rearwardly bent ends connected to the forward ends of said lateral connection-chambers.
18. In a steam-boiler superheater, the combination of a vertical casing or header having an upper port or opening for communication with a T-head compartment and lateral open-ended tubular ears or connection-chambers, superheater-pipes registering with the open ends of the lateral connection-chambers, packing interposed between said chambers and the pipe ends, glands or followers bearing on collars on the pipes, and bolts connecting said glands or followers.
19. In a steam-boiler superheater, the combination of a vertical casing or header

having an upper port or opening for communication with a T-head compartment and lateral open-ended tubular ears or connection-chambers provided with end recesses, 5 packing inserted in said recesses, superheater-pipes registering with the open ends of the lateral connection-chambers and bearing on the packing, glands or followers bearing on collars on the pipes, and bolts connecting 10 said glands or followers.

16. In a steam-boiler superheater, the combination of a vertical casing or header having an upper port or opening for communication with a T-head compartment and 15 lateral open-ended tubular ears or connection-chambers, superheater-pipes registering with the open ends of the lateral connection-chambers, packing interposed between said chambers and the pipe ends, rocking or 20 curved-faced glands or followers bearing on collars on the pipes, and bolts connecting said glands or followers.

17. In a steam-boiler superheater, the combination of a vertical casing or header 25 having an upper port or opening for communication with a T-head compartment and lateral open-ended tubular ears or connection-chambers, superheater-pipes having straight ends registering with the open rear 30 ends of the lateral connection-chambers, superheater-pipes having downwardly, rearwardly and outwardly bent ends registering with the open forward ends of the lateral connection-chambers, glands or followers 35 bearing on collars on the pipes, and bolts connecting said glands, the bolts adjoining the bent pipes being cleared for access by the outward bends of said pipes.

18. A vertical casing or header for steam-boiler superheaters having an upper port or 40 opening for communication with a T-head compartment, and lateral tubular ears or connection-chambers which are open at both their forward and rear ends for connection 45 with the forward ends of superheater-pipes.

19. A vertical casing or header for steam-boiler superheaters having an upper port or 50 opening for communication with a T-head compartment, and lateral tubular ears or connection-chambers which are open at both their forward and rear ends for connection 55 with the forward ends of superheater-pipes

and are recessed at their ends for the reception of packing.

20. A pair of superheater-pipes for steam-boiler superheaters which are connected at their rear ends in U form, and having one of their forward ends straight and the other bent in U form, both ends being provided with collars for connection to headers. 60

21. A pair of superheater-pipes for steam-boiler superheaters which are connected at their rear ends in U form, and provided with collars on their forward ends for connection to headers, and are bent in U form downwardly, rearwardly, and outwardly adjacent to their forward ends. 65

22. In a steam-boiler superheater, the combination of a T-head divided into supply and delivery compartments, a plurality of 70 saturated-steam headers and superheated-steam headers, disposed alternately on the T-head and connected thereto with the capacity of independent attachment and removal, said saturated and superheated 75 steam headers communicating, respectively, with the supply and the delivery compartments, and a plurality of pairs of superheater-pipes, the forward ends of each of which are connected to the sides of a saturated and a superheated steam header, respectively. 80

23. In a steam-boiler superheater, the combination of a vertical casing or header, and a plurality of superheater-pipes communicating directly therewith through both the 85 front and back ends of lateral connections.

24. In a steam-boiler superheater, the combination of a plurality of vertical saturated-steam headers and vertical superheated-steam headers, a T-head extending transversely in the smoke-box and having two compartments to which the saturated and the superheated steam headers are, respectively, connected, and a plurality of pairs of 90 superheater-pipes extending in U form rearwardly from the headers, the forward end of one pipe of each pair being connected to a saturated-steam header and the other end to a superheated-steam header. 95
